UNITED STATES PATENT OFFICE

HERMANN IDEL, OF DUISBURG, GERMANY, ASSIGNOR TO DEMAG. AKTIENGESELLSCHAFT, OF DUISBURG, GERMANY

APPARATUS FOR COOLING THE MANDRELS OF TUBE-ROLLING MILLS

Application filed June 16, 1927, Serial No. 199,381, and in Germany April 12, 1927.

The effective operation of tube rolling mills requires that the mandrels employed be continuously cooled, because they are subjected by the work to very exceptional degrees of heat. For this purpose the mandrels are made hollow and are subjected to the action of circulating cooling water during operation.

According to the invention an apparatus is provided in such manner that when the mandrel is advanced into the working position it is automatically put into communication with the water feed pipe, and immediately thereupon it actuates a closure member, which admits water to the mandrel. Vice versa, the pipe connections are broken on the return of the mandrel after each working operation, and at the same time the inlet for the water is closed.

According to the invention, moreover, a valve is provided on the stationary bed and is held in closed position by means of a spring, and the valve is provided with a tubular extension serving also as a guide for the valve, the extension being adapted to contact with a mouthpiece when the mandrel is advanced, the mouthpiece forcing the valve back to open it and thereby to allow the water to flow through to the mandrel.

One form of apparatus according to the invention is illustrated in the accompanying drawing in its application to a mill with inclined rolls.

In the drawings:

Figure 1 illustrates the apparatus in longitudinal section;

Figure 2 is a partial plan corresponding to Figure 1, and

Figure 3 shows an important part of the apparatus on an enlarged scale in longitudinal section.

1 is one of the two inclined rolls which work together with the head 2 on the mandrel 3 which is hollow. The rear end of the hollow mandrel 3 is connected in known manner by screw threaded parts to the head 4 which can be advanced or retracted and which is held in known manner by the abutment 5 in the working position. The head or bearing 4 is secured and released as shown

in the drawing on movement of the abutment 5 by means of a pneumatic or hydraulic device 6. The head or bearing 4 is connected to a rack 7 which is disposed parallel below the mandrel, and in which engages the 55 toothed pinion 8 driven by a motor. Adjacent the head or bearing 4, a valve casing 10 is secured on the bed 9, in which the valve member 11 is subject to the action of the spring 23 which has for its object to maintain the valve member 11 closed (Figures 3 and 2). The water feed pipe 12 is connected to the valve casing 10 and at the rear of the valve member 11 a tubular member 13 is provided through which the water passes, the 60 tubular member 13 being connected to the valve member 11 to serve as a guide and to pass through the stuffing box 14 provided at the end of the valve casing 10. When the valve member 11 is in the open position illustrated in Figure 3, water passes through the slots 15 into the bore of the tubular member 13. The free end of the tubular member 13 is provided with a conical mouthpiece 16 which in the working position of the mandrel 3 is pressed tight against a packing or seating ring 17 mounted in the casing 18. Passages 19 are provided in the casing 18, and connected with the bent pipe 20, the end 21 of which passes into the mandrel 3. When 65 70 75 80 85 the valve member 11 closes upon its seat the supply of water is cut off.

The manner of operation of the cooling apparatus will be readily understood from the foregoing description and the drawing. The 85 apparatus operates as follows:

When the mandrel 3 is in the retracted position the head 4 is also drawn back with the casing 18 away from the mouthpiece 16 so that the valve member 11 is held in the closed 90 position under the action of the spring 23. As the mandrel 3 is advanced the packing or seating ring 17 presses against the conical head 16 of the tubular member 13 and forces it back (see Figure 3), so that the cooling 95 water flows from the pipe 12 through the slots 15 into the pipe 13. The cooling water leaves this pipe 13 and passes through the passages 19 into the pipe 20 and thence, as shown in the drawing, into the mandrel 3, thereupon the 100

water passes again into the head 4 through the annular passage surrounding the pipe 20 and is carried away along the channel 22.

The use of the invention is not confined to the construction illustrated, but may be used generally for tube rolling mills.

I claim:

- 10 1. Means for cooling mandrels of tube rolling mills consisting in combination of a mandrel adapted to be cooled and having an inlet for the cooling liquid, means for causing the movement of the mandrel into and out of the working position and means operable only on the mandrel reaching its working position for the admission of the cooling liquid into the said inlet.
- 20 2. An apparatus for cooling mandrels of tube rolling mills consisting in combination of a mandrel adapted to be retracted from its working position and to be cooled, a head within which the said mandrel is supported said head comprising a mouthpiece for the admission of the cooling liquid, and a stationary spring closed valve adapted by a hollow extension to be opened on contact with the said mouthpiece for passage of the cooling liquid through the said extension to the mandrel.

HERMANN IDEL.
